LIFTING JACK

Erich Grassmann, Gelsenkirchen, Germany

Application January 19, 1939, Serial No. 251,752
In Germany January 18, 1938

15 Claims.

(Cl. 254—1)

This invention relates to lifting devices or jacks. The lifting device according to the invention comprises a continuous or linked band of metal which can be wound into spiral form, two members, namely a rotor and a stator, disposed concentrically so as to enclose an annular space therebetween, a helically ascending guide track for said band in said annular space, a slot in the outer member of said two concentric members through which said band can pass to said guide track, means for engaging said band with the inner member of said two concentric members and means for rotating the rotor relatively to the stator.

15 The structural height of the device is low and the device is inexpensive to construct, yet it is capable of being used for raising loads to a height of several metres and is therefore particularly suitable for lifting aircraft, motor cars, machinery, buildings, etc. When collapsed, the device occupies only a small space and is therefore particularly adapted for use in military work as by the engineering corps. It can be used as a pressure device or as a supporting device or 20 lifting device and as a conduit for gases and liquids which can be easily made tight in places where rigid pipes cannot be employed. The metal or linked band can be provided with one or more rows of projecting pins and perforations 25 along its edges, in such a way that, when it is formed into a tube, the projecting pins in one convolution of the helix engage in the perforations of the adjacent convolution, so that the helical convolutions are connected together so 30 that they can resist pressure without bending.

35 The stator and rotor can be interchanged as desired, depending upon whether the tube is to rotate while being formed or whether the tube is to be formed without rotating.

40 It is advantageous to fit the rotor and stator in the centre of a rotatable cylindrical casing, which contains the band wound in the form of a spiral. It is also possible to separate the casing which contains the band and the driving 45 means from one another if an eccentric arrangement of the head of the lifting device is desired.

The casing which contains the band is preferably mounted on rollers or balls in order to reduce friction when the band is being extended into 50 tubular form. The helical guide track for the band can consist of or be provided with rollers.

In order to form the band into a cylindrical tube of which the individual convolutions are of conical form and engage one within another, so 55 as to project one above another with overlapping

edges, the edge of the metal band may be curved. Then the radius of the tube formed from the band remains constant and the tube is able to support pressure without pins and perforations being arranged in the edges of the band.

In order to reduce friction on the helically ascending guide track and to avoid damage to the edges of the band which carry the load, the rollers of the helical track can be connected together by straps and a chain constituted by blocks 10 which are linked together may be carried by the rollers. The rollers can be of conical shape, the conicity depending on the radius of the helical guide track. The connecting straps are provided with elongated holes for the purpose of 15 increasing the flexibility.

The blocks forming the chain are preferably bevelled or tapered at the joints in such a way as to be movable in all directions.

In order that the invention may be readily 20 understood and carried into effect, a lifting device constructed in accordance with the invention is illustrated by way of example in the accompanying drawings, in which:

Figure 1 is a vertical section through the base 25 of the lifting device,

Figure 1a is a horizontal half section on the lines 1a—1a of Figure 1,

Figure 2 is a vertical section through the guide track showing a roller, the chain of blocks and 30 the steel band.

Figure 3 is an elevation showing the rollers and part of the chain and steel band,

Figure 3a is a horizontal section through a part of the chain of blocks,

Figure 4 is a part plan of the rollers,

Figure 5 is a side view of one of the straps by which the rollers are connected,

Figure 6 is a detail view of another form of band, and

Figure 7 is a perspective view of the device partly broken away.

Referring to the drawings, the box-like casing 1 carries at its centre the cylindrical stator 3 which has longitudinal grooves 21 in the outer 45 surface. Around the stator is mounted on ball bearings 3 a cylindrical rotor 11 in the inner surface of which a helical guide track 22 is cut out. Around the rotor 11 and between ball bearings 4 is mounted a drum 25 which carries 50 a spirally wound metal band 5. (Figure 1.) The rotor 11 is provided with an opening 24 (Fig. 1a) for guiding the band to the annular space 26 which is enclosed between the rotor and stator. The band is provided at its lower edge with a 55

series of holes 6 and carries at its upper edge a series of pins 7 (Figure 2). The edge 30 of the band may be of circular curvature as shown at 29 in Figure 6. On the guide track 22, which preferably slopes upwards towards the inside 5 (Figs. 1 and 2), are mounted conical rollers 10 which are connected together by means of straps 12. The straps 12 are provided with elongated eyes 20 (Figure 5) for enabling the chain formed 10 to be movable in all directions. The rollers 12 support an endless chain formed of blocks 9 which possess guide slots 23 for the edge of the band 5. In order that the chain may be movable to all sides the bolt holes 19 at the joints are of 15 double conical form, as shown in Figure 3a.

15 The steel band 5 which passes through said slot 24 in the rotor 11 engages by means of its pins 7 in the grooves 21 in the stator 8. When the rotor 11 is rotated through the agency of 20 the toothed wheels 13, 14 by turning the spindle 15, the band is raised by means of the chain of blocks 9 carried on the guide track 22 and thus formed into a cylindrical tube. Rollers 2 (Figure 1a) press the pins 7 in the convolution 27 into 25 the holes 6 in the convolution 28, so that the cylindrical tube is able to resist axial pressure. The band carries a head plate 17 having a turntable 18 for raising objects. The rollers 10 and 30 the blocks 9 both of which form an endless chain travel round inside the rotor. The lifting device can be transported by rolling it on its side 31 or it can be carried.

35 It will be noted that the construction shown and described will serve admirably to accomplish the objects stated above. It is to be understood, however, that the construction disclosed above is intended merely as illustrative of the invention and not as limiting as various modifications therein may be made without departing from 40 the invention as defined by a proper interpretation of the claims which follow.

I claim:

45 1. A lifting device comprising a metal band capable of being wound into spiral form, two members disposed concentrically so as to enclose an annular space therebetween, a helically ascending guide track for said band in said annular space, a slot in the outer of said two concentric members through which said band can 50 pass to said guide track, means for engaging said band with the inner of said two concentric members and means for rotating one of said concentric members relatively to the other.

55 2. A lifting device comprising a metal band capable of being wound into spiral form, two members disposed concentrically so as to enclose an annular space therebetween, a helically ascending guide track for said band formed in the inner surface of the outer of said concentric 60 members, a slot in the outer of said concentric members through which said band can pass to said guide track, grooves in the outer surface of the inner of said concentric members, projections on the band for engaging said grooves and 65 means for rotating one of said concentric members relatively to the other.

70 3. A lifting device comprising a metal band capable of being wound into spiral form, two members disposed concentrically so as to enclose an annular space therebetween, a helically ascending guide track for said band in said annular space, a slot in the outer of said concentric members through which said band can pass to 75 said guide track, means for engaging said band with the inner of said concentric members, pro-

jections along one edge of said band, holes along the opposite edge of the band in which said projections on the edge of the adjacent convolution engage when the band is wound into helical form and means for rotating one of said concentric members relatively to the other.

5 4. A lifting device comprising a metal band capable of being wound into spiral form, a cylindrical stator having grooves in its outer surface, a rotor enclosing said stator so as to form an annular space therebetween, a helically ascending guide track for said metal band in the inner surface of said rotor, a slot in said rotor through which said band can pass to said guide track, 10 projections on said band for engaging said grooves in said stator, and means for rotating said rotor relatively to said stator, so as to extend the band in the form of a tube in said annular space.

15 5. A lifting device comprising a metal band capable of being wound into spiral form, two members disposed concentrically so as to enclose an annular space therebetween, a helically ascending guide track for said band in said annular space, rollers on said guide track, a slot 20 in the outer of said two concentric members through which said band can pass to said guide track, means for engaging said band with the inner of said concentric members and means for rotating one of said concentric members relatively to the other.

25 6. A lifting device comprising a metal band capable of being wound into spiral form, two members disposed concentrically so as to enclose an annular space therebetween, a casing arranged to rotate on bearings around said concentric members in which said band is disposed in spiral form, a helically ascending guide track for said band in said annular space, a slot in the outer of said two concentric members through 30 which said band can pass to said guide track, means for engaging said band with the inner of said concentric members and means for rotating one of said concentric members relatively to the other.

35 7. A lifting device comprising a metal band capable of being wound into spiral form and having a curved edge, two members disposed concentrically so as to enclose an annular space therebetween, a helically ascending guide track 40 for said band in said annular space, a slot in the outer of said two concentric members through which said band can pass to said guide track, means for engaging said band with the inner of said two concentric members and means for 45 rotating one of said concentric members relatively to the other.

8. A lifting device comprising a metal band capable of being wound into spiral form, two members disposed concentrically so as to enclose an annular space therebetween, a helically ascending guide track for said band in said annular space, rollers on said guide track, straps connecting said rollers so as to form an endless chain, a slot in the outer of said two concentric members through which said band can pass to 55 said rollers, means for engaging said band with the inner of said two concentric members and means for rotating one of said concentric members relatively to the other.

60 9. A lifting device comprising a metal band capable of being wound into spiral form, two members disposed concentrically so as to enclose an annular space therebetween, a helically ascending guide track for said band in said annular 65 space.

lar space, rollers on said guide track, straps connecting said rollers to form an endless chain, blocks linked together to form an endless chain carried by said rollers for supporting said band, 5 a slot in the outer of said two concentric members through which said band can pass to said blocks, means for engaging said band with the inner of said two concentric members and means for rotating one of said concentric members relatively to the other.

10. A lifting device as claimed in Claim 9, wherein said blocks are provided with grooves for receiving the edge of the metal band.

11. A lifting device as claimed in Claim 5, 15 wherein said rollers are conical and the guide track on which they are supported slopes up inwardly towards the centre.

12. A lifting device comprising a metal band capable of being wound into spiral form, a cylindrical stator having vertical grooves in its outer surface, a rotor enclosing said stator so as to form an annular space therebetween, a casing mounted to rotate around said rotor and stator in which said band is spirally wound, a helically ascending 20 guide track for said metal band in the inner surface of said rotor, rollers on said guide track, a slot in said rotor through which said band can pass to said guide track, projections on said band for engaging said grooves in said stator, projections along one edge of the band, holes along 25 the opposite edge of the band in which the projections of the adjacent convolutions engage when the band is wound into helical form, and

means for rotating said rotor relatively to said stator.

13. A lifting device comprising a metal band capable of being wound into spiral form, a cylindrical stator having grooves in its outer surface, 5 a rotor enclosing said stator so as to form an annular space therebetween, a helically ascending guide track for said metal band in the inner surface of said rotor, a slot in said rotor through which said band can pass to said guide track, projections on said band for engaging said grooves in said stator, 10 projections along one edge of the band, holes along the opposite edge of the band in which the projections of the adjacent convolutions engage when the band is wound into helical form, and means for rotating said rotor relatively to said stator. 15

14. A lifting device comprising a metal band having a curved edge and capable of being wound into spiral form, a cylindrical stator having 20 grooves in its outer surface, a rotor enclosing said stator so as to form an annular space therebetween, a helically ascending guide track for said metal band in the inner surface of said rotor, a slot in said rotor through which said band can 25 pass to said guide track, projections on said band for engaging said grooves in said stator, and means for rotating said rotor relatively to said stator.

15. A lifting device as claimed in Claim 1, 30 wherein the band is composed of links.

ERICH GRASSMANN.
